CAP FOR A LIQUID FERTILIZER APPLICATOR

Frank J. Lex, Shreveport, La., assignor to Keokuk Steel Casting Company, Keokuk, Iowa, a corporation of Iowa

Filed Nov. 6, 1963, Ser. No. 77,312

Term of patent 14 years

(Cl. D35—2)

FIG. 1 is a perspective view of a cap for a liquid fertilizer applicator showing my new design,

FIG. 2 is a side elevation taken from the opposite side of FIG. 1,

FIG. 3 is a top view thereof,

FIG. 4 is a bottom view thereof, and

FIG. 5 is a rear end view thereof.

I claim:

The ornamental design for a cap for a liquid fertilizer applicator, as shown.
